UNITED STATES PATENT OFFICE.

ALLINGTON H. KRAMER, OF AURORA, COLORADO.

BEET-TOPPER.

1,235,490.

Specification of Letters Patent. Patented July 31, 1917.

Application filed July 14, 1916. Serial No. 109,340.

To all whom it may concern:

Be it known that I, ALLINGTON H. KRAMER, a citizen of the United States, residing at Aurora, in the county of Adams 5 and State of Colorado, have invented new and useful Improvements in Beet-Toppers, of which the following is a specification.

This invention relates to beet topers and it consists in the novel features hereinafter 10 described and claimed.

An object of the invention is to provide a machine of simple and durable structure having means for removing the tops from the beets while they are in position in the 15 ground, there also being means provided for directing the foliage leaves of the beet tops toward the means which sever the tops from the bodies of the beets.

A further object of the invention is to 20 provide in a machine of the character indicated a pivotally mounted frame for carrying the beet topper and the foliage engaging means so that the said topper and the said means may ride vertically as the machine 25 is drawn over the ground and thus the tops will be removed from the beets at uniform distances from the upper ends of the beets.

Another object of the invention is to 30 provide in combination with a topper of the character indicated a fender plate or blade adapted to cast the beet tops to one side whereby they will deposit in a row as the machine is drawn along the ground.

35 In the accompanying drawings:—

Figure 1 is a side elevation of the beet topper.

Fig. 2 is a top plan view of the same.

Fig. 3 is a longitudinal sectional view of 40 the same.

Fig. 4 is a detail plan view of parts showing adjacent parts in section.

The beet topper comprises a frame 1 which is mounted at its rear portion upon 45 an axle 2 having traction wheels 3 mounted at the ends thereof in the usual manner. A draft clevis 4 is adjustably mounted at the forward end of the frame 1 and any suitable draft appliance may be carried by the said 50 clevis. A shaft 5 is journaled for rotation at the forward portion of the frame 1 and a sprocket wheel 6 is mounted at one end of the said shaft. A sprocket wheel 7 is mounted upon the axle 2 and a sprocket 55 chain 8 is trained around the sprocket wheels 6 and 7 and is adapted to transmit

rotary movement from the axle 2 to the shaft 5. The forward portion of the frame 1 is mounted upon a pivoted truck 9 and a lever mechanism 10 is provided upon the 60 forward portion of the frame 1 for raising and lowering the said frame with relation to the truck 9.

The side bars of a supplemental frame 11 are pivotally connected with the shaft 5 and 65 the forward ends of the said side bars are extended in advance of the said shaft and carry a weight 12 which is adjustably mounted upon the said supplemental frame. A cross bar 13 is carried at the rear end 70 of the supplemental frame 11 and a shaft 14 is journaled for rotation in the said cross bar. The shaft 14 carries at its lower end a concaved disk 15 which is arranged to rotate in a plane at an acute angle to a horizontal. The said disk 15 is forwardly and 75 downwardly inclined so that its forward edge portion is at a lower elevation or level than the side and rear portions of its edge. Brackets 16 are mounted upon the rear portion 80 of the frame 11 and a shaft 17 is journaled for rotation upon the said brackets. The shaft 17 carries a beveled gear wheel 18 which meshes with a similar gear wheel 19 mounted upon the shaft 14. A sprocket 85 wheel 20 is mounted upon the shaft 17 and a sprocket wheel 21 is mounted upon the shaft 5. A sprocket chain 22 is trained around the sprocket wheels 20 and 21 and is adapted to transmit rotary movement 90 from the shaft 5 to the shaft 17. Through the intermeshing gear wheels 18 and 19 rotary movement is transmitted from the shaft 17 to the shaft 14 whereby the disk 15 is rotated when the machine is in opera- 95 tion.

A vertically disposed sleeve 23 is mounted upon the frame 1 and a rod 24 is slidably mounted in the said sleeve. The lower end of the rod 24 is pivotally connected with the 100 intermediate portion of the frame 11. A coil spring 25 is interposed between the lower end of the sleeve 23 and the frame 11 and the said spring 25 is under tension with a tendency to resiliently hold the rear portion of the frame 11 in a lowered position. A lever 26 is fulcrumed upon the frame 1. A chain 27 connects the forward end of the lever 26 with the intermediate portion of the frame 11. Therefore it will 105 be seen that the rear portion of the frame 11 is held in a lowered position under the

tension of the spring 25 but when the attachment carried by the frame 11 comes in contact with elevated places in the ground or soil the rear portion of the frame 11 may swing in an upward direction whereby the beet topping means are carried over the said elevated places.

Bars 28 are adjustably connected at their upper ends with the intermediate portions 10 of the side bars of the frame 11 and bars 29 are similarly connected with the side bars of the frame 11. A shaft 30 is journaled for rotation at the lower ends of the bars 28 and 29 and carries a roller 31. The said roller 31 is provided at its periphery with a number of outstanding radially disposed lugs 32. A sprocket wheel 33 is mounted upon the shaft 30 and sprocket wheel 34 is mounted upon the shaft 5. A sprocket chain 20 35 is trained around the sprocket wheels 34 and 33 and is adapted to transmit rotary movement from the shaft 5 to the shaft 30. Curved fender blades 36 are adjustably secured by means of clips 37 to the bars 28 and the said blades are located beyond the ends of the roller 31. The rear ends of the blades 36 are triangular in plan and lie between the end portions of the periphery of the roller 31 and the adjacent edge portion 30 of the disk 15 and serve as means for directing the beet tops to the periphery of the disk 15 and also serve as means for holding the roller 31 in proper position upon the beet tops while the roller is passing over the beets in the ground. The roller 31 rotates at a slightly increased rate of speed than that at which the machine moves in a forward direction, consequently as the roller 31 encounters the beet tops the said roller 40 passes them in a backward direction so that the disk 15 which follows the roller 31 may encounter the tops and sever the same from the bodies of the beets. The weight 12 carried at the forward portion of the frame 11 counter-balances the rear portion of the said frame and the parts carried thereby.

Arms 38 are pivotally connected at their forward ends with the shaft 5 and the said arms at their rear ends carry digging shares 39. A shaft 40 is journaled for rotation at the rear ends of the arms 38 and carries a sprocket wheel 41. A sprocket wheel 42 is mounted upon the shaft 5 and a sprocket chain 43 is trained around the sprocket wheels 41 and 42 and is adapted to transmit rotary movement from the shaft 5 to the shaft 40. Soil shakers 44 are mounted for reciprocatory movement behind the digging shares 39 and levers 45 are fulcrumed from supports depending from the arms 38. The upper ends of the levers 45 are connected with cranks provided upon the shaft 40 and the lower ends of the said levers are operatively connected with the soil shakers 44.

The operation of the beet topping machine is as follows:—As the machine is being drawn over the surface of the ground the roller 31 encounters the beet tops and the lugs 32 carried by the said roller move the foliage of the beets in a rearward direction between the fenders 36. The inner edge portions of the fenders 36 direct any of the beet tops with which they come in contact toward the periphery of the disk 15. As the machine is being drawn over the surface of the ground the disk 15 is rotated as hereinbefore described and as the periphery of the said disk comes in contact with the beet tops the tops are severed from the bodies of the beets and the tops fall upon the upper surface of the disk 15. A fender plate 46 is mounted upon the frame 11 above the upper surface of the disk 15 and to one side of the center thereof and as the beet tops come in contact with the said fender plate they are scraped from the upper surface of the disk and are deposited in a row upon the surface of the ground.

After the tops have been removed from the bodies of the disks as hereinbefore described, the digging shares 39 pass under the body portions of the beets and the said beets are lifted by the shares from the soil. At the same time the soil shaking elements 44 are reciprocated and the beets are subjected to an agitation which loosens any soil which might adhere to them and this soil falls back in the furrows which have been opened by the shares 39 while the beets are permitted to fall from the rear ends of the digging shares and deposit upon the surface of the soil.

From the foregoing description taken in conjunction with the accompanying drawings it will be seen that a beet topper of simple and durable structure is provided and that the same includes an element for removing the tops from the bodies of the beets while the beets are in position in the ground also means for disposing the foliage of the beets toward the said topping means and fenders for regulating the depth at which the topping means will operate in the ground and also for directing the foliage toward the said topping means.

Having described the invention what is claimed is:—

1. A beet topper comprising a frame, a disk journaled for rotation thereon, a roller journaled for rotation in advance of the disk, means for rotating the disk, means for rotating the roller and fender blades positioned at the ends of the roller and having rear portions disposed between the periphery of the roller and the periphery of the disk.
2. A beet topper comprising a disk journaled for rotation, means for rotating the disk, a roller journaled for rotation in ad-

vance of the disk, means for rotating the roller, fender blades located at the ends of the roller, said blades having triangular rear end portions which extend between the ends of the roller and which lie between the periphery of the roller and the adjacent portion of the periphery of the disk.

In testimony whereof I affix my signature in presence of two witnesses.

ALLINGTON H. KRAMER.
